(57) **CLAIM**

The ornamental design for a tape spool support for tape cartridge, as shown and described.

DESCRIPTION

FIG. 1 is a perspective view of a tape spool support for tape cartridge;

FIG. 2 is an enlarged perspective view thereof;

FIG. 3 is a top view thereof;

FIG. 4 is a left side view thereof;

FIG. 5 is a right side view thereof;

FIG. 6 is a perspective view of another embodiment of a tape spool support for tape cartridge;

FIG. 7 is an enlarged perspective view thereof;

FIG. 8 is a top view thereof;

FIG. 9 is a left side view thereof; and,

FIG. 10 is a right side view thereof.

The broken lines define the bounds of the claimed design but form no part of the claimed design.
